APPARATUS, INCLUDING A MANUALLY POSITIONED UPPER DIE FOR SHAPING ARMATURE COILS

Bruce W. Markey, Aliquippa, Pa., assignor to
Jones & Laughlin Steel Corporation, Pittsburgh,
Pa., a corporation of Pennsylvania

Application February 15, 1945, Serial No. 578,095

6 Claims. (Cl. 153—21)

1

This invention relates to the processing of armature coils and, in particular, to the shaping of the straight sides of the coil prior to the application thereto of the usual insulating tape.

The practice followed heretofore in making armature coils has been to place the straight coil sides between shaping members, after the coils have been wound and pulled out, and then to hammer on the upper shaping member. This procedure does not insure the proper sizing and shaping of the coil sides and, in addition, is relatively slow because of the amount of manual labor involved. I have invented a novel apparatus and method for shaping armature coil sides capable of speedily and accurately imparting thereto precisely the desired shape whereby, after wrapping with insulating tape, they will fit the armature slots very closely. In a preferred embodiment and practice of the invention, I provide a press including a lower die which is relatively fixed, and a movable upper die, as well as power means for forcing the upper die toward the lower die. I also heat the lower die. The coil sides are heated by contact therewith and the shaping operation is thereby facilitated.

Further details and advantages of the invention will become apparent during the following complete description which refers to the accompanying drawings illustrating the preferred embodiment.

In the drawings,

Figure 1 is a front elevation of the apparatus;
Figure 2 is an end elevation thereof;

Figure 3 is a partial section to enlarged scale taken along the plane of line III—III of Figure 1;

Figure 4 is a partial section to enlarged scale taken along the plane of line IV—IV of Figure 2;

Figure 5 is a plan view of one form of armature coil; and

Figure 6 is a side elevation thereof.

Referring in detail to the drawings, the apparatus which I have devised for carrying out the invention comprises a table 10 having a pair of vertical-slide press units 11 and 12 mounted thereon. These units are identical and, accordingly, only one will be fully described. Each press unit 11 comprises an overhanging post 13 secured to the table by screws 14 and supporting a power cylinder 15 and a guide bracket 16. The cylinder 15 has flanges 17 and is secured to the posts by bolts 18. The guide bracket 16 is secured to the posts by screws 19 and has a guide channel 20 extending vertically through the front face thereof provided with liners 21. A slide 22 reciprocable through the guide channel is held

2

in place by gibbs 23 secured to the bracket by screws 24. A piston 25 in the cylinder 15 is constantly urged upwardly by a compression spring 26 and has its piston rod 27 secured to the upper end of the slide 22. The portion of the bracket behind the channel 20 forms an oil reservoir 28 and is provided with a filling hole and plug 29. A wick 30 extends through a hole in the bottom of the channel 20 to feed oil to the contacting surfaces of the liners 21 and slide 22.

The piston 25 is operated by fluid under pressure supplied from any convenient source through a pipe 31 under the control of valves 32 and 33. When fluid under pressure is admitted to the cylinder 15 by operating the valves, the piston is forced downwardly, compressing the spring 26 and actuating the slide 22 on a downward stroke. The valves 33 permit independent operation of the slides of the two press units. If it is desired to operate them both simultaneously, the valves 33 are left open and the control is effected by operating valve 32.

A relatively fixed bottom die 34 in the form of an elongated bar rests on the table 10. A V-shaped trough 35 formed in the upper face of the bar extends the full length thereof. The bottom of the die has a channel 36 accommodating a resistance heating element 37 secured thereto by any convenient means (not shown). Thermal conducting pins 38 extend upwardly through the die from the channel 36 into the neighborhood of the trough 35. When the element 37 is energized by connecting it to a suitable source of electric current, the heat generated therein flows upwardly through the pins 38 toward the top surface of the die 34. The pins 38 are spaced longitudinally of the die, being arranged in two rows, one on each side of the trough 35.

The trough 35 in the die 34 is adapted to receive one of the straight sides of an armature coil 39 when the coil is so disposed that it lies in a plane making approximately 45 degrees with the horizontal. An upper die 40 in the form of an angle bar having a length somewhat less than that of the coil side is secured to a manipulating rod 41 having a handle 42. The slide 22 has a head 43 adapted to engage the upper edge of the die 40, having a V-shaped slot 44 therein to accommodate the die and a notch 45 to receive the rod 41.

It will be apparent that when a coil 39 after having been wound and pulled out in the known manner, has one of its straight sides disposed in the trough 35 of die 34, as shown in Figure 3, and the die 40 is disposed thereon, operation of one

of the press units will cause the slide 22 thereof to engage the die 40 and compress the coil side between it and the die 34, thereby shaping the coil side precisely to rectangular shape and the desired cross-sectional dimensions so that, after it has been wrapped with insulating tape, it may be pressed into the armature slots with a snug fit. After shaping one side of the coil, the coil is reversed and the other side is similarly treated. Similar shaping operations may be performed 10 after the insulating tape has been wrapped on the coil.

Armature coils vary considerably in the ratio of the thickness of the section thereof to the depth. For various types of coils, therefore, it is desirable to move the die 34 laterally on the table. For this purpose, I provide thrust blocks 46 secured to the table 10 in line with the two press units. Adjusting screws 47 threaded through tapped holes in the blocks 46 engage thrust bearings 48 seated in suitable counterbores in the front side of the bar or die 34. Guide pins 49 extending from the rear face thereof pass through holes in guide blocks 50 secured to the table 10. Compression springs 51 between the blocks 50 and the die 34 constantly urge the latter toward the front side of the table. When it is desired to adjust the die 34 laterally under the slides 22 of the press units, it is only necessary to turn the screws 47 in the proper direction.

It will be noted that die 34 extends under the slides of both the press units. This permits the shaping of the sides of coils in a wide range of sizes. For large coils, both slides may be employed to actuate the upper die, the upper and lower die under the respective slides and press heads being in lengthwise registry. A plurality of upper dies are provided to fit the various coil sizes and sectional shapes to be processed. Where relatively small coils, such as those shown in Figure 1, are being treated, it is convenient to shape one side of the coil in one unit and the other side in the other unit, the coil being passed from one operator to another after the first shaping.

The heat supplied to the bottom die by the element 37 is transmitted to the coil sides. If the coils are formed from wire having insulation composed partly of organic materials, they will be somewhat softened by the heat, thereby facilitating the shaping operation and causing the several turns to adhere to each other when compressed, thus converting the coil side from a relatively irregular bundle of loose wires into a fairly dense and solid mass of precise shape and dimensions. As a result, the coils may readily be applied to the armature for which they are intended, after the application of the usual wrapping of insulating tape and varnish or the like.

The advantages of the invention will be obvious from the foregoing description and explanation. In the first place, the utilization of power means for actuating the upper die makes it possible to apply a heavy shaping pressure. In the second place, the operation may be quickly performed even by a relatively unskilled laborer after a limited period of instruction. The apparatus is simple in structure and operation and is thus relatively inexpensive to manufacture and maintain. The shaping operation is rendered much more effective by the heating of the lower die. The apparatus is adapted, as previously explained, to the processing of coils varying widely in size. The lateral adjustability of the lower die permits the vertex of the trough therein to be properly positioned relatively to the vertex of the slot 44 in the

head of the slide so that the coil side is given the proper shape.

Although I have illustrated and described but a preferred embodiment and practice of the invention, it will be understood that changes in the apparatus and procedure disclosed may be made without departing from the spirit of the invention or the scope of the appended claims.

I claim:

1. In a machine for shaping armature coils or the like, said machine having a press head, a manually positioned upper die adapted to be pressed by said press head, a lower die adapted to cooperate with said upper die, said lower die forming with said upper die the exact configuration in which one side of an armature coil is to be press formed therebetween, the improvement comprising, means for adjusting said lower die in any of a number of different positions transversely of the vertical plane from side to side through the center of said press head, whereby armature coils of varying cross sections can be press formed.

2. In a machine for shaping armature coils or the like, said machine having a press head, a manually positioned upper die adapted to be pressed by said press head, a lower die adapted to cooperate with said upper die, said lower die forming with said upper die the exact configuration in which one side of an armature coil is to be press formed therebetween, the improvement comprising, in combination, means for adjusting said lower die in any of a number of different positions transversely of the vertical plane from side to side through the center of said press head, and heating means for said lower die, whereby armature coils of varying cross sections can be more easily press formed while being so heated.

3. In a machine for shaping armature coils or the like, said machine having a press head, a manually positioned upper die adapted to be pressed by said press head, a lower die adapted to cooperate with said upper die, said lower die forming with said upper die the exact configuration in which one side of an armature coil is to be press formed therebetween, the improvement comprising, thrust members for adjusting said lower die in any of a number of different positions transversely of the vertical plane extending from side to side through the center of said press head and resilient means for maintaining said lower die against said thrust members, whereby armature coils of varying cross sections can be press formed.

4. In a machine for press forming armature coils or the like, in combination, a press head adapted to reciprocate on a vertical axis, said press head having an inverted-V recess in the bottom extending from side to side thereof, an upper die adapted to be manually positioned on one side of a coil to be press formed, said upper die having an upper surface corresponding to said recess in said press head and adapted to cooperate therewith, said upper die further having a lower surface conforming to the shape of and substantially cover at least two of the surfaces of the side of said coil which is to be press formed, and a lower die, said lower die having a V-shaped recess extending from side to side thereof conforming to the shape of two lower surfaces of the side of said coil which is to be press formed, said lower die further being adjustable transversely of the vertical plane bisecting said recess in said press head from side to side thereof, whereby when one side of a coil to be press formed is placed in said lower die and said upper die is positioned

thereon, said press head may be actuated to press said dies together a predetermined amount to press form said side of said coil and for each adjustment of said lower die a coil of different cross sectional dimension with a corresponding upper die can be press formed.

5. In a machine for press forming armature coils or the like, in combination, a press head adapted to reciprocate on a vertical axis, said press head having an inverted-V recess in the bottom extending from side to side thereof, an upper die adapted to be manually positioned along one side of a coil of substantially rectangular cross section to be press formed, said upper die having an upper surface corresponding to said recess in said press head and adapted to cooperate therewith, said upper die further having a lower surface substantially in an inverted-V shape conforming in angle and length substantially to the two upper sides of said coil when resting on a lower die, a lower die, said lower die having a V-shaped recess extending from side to side thereof conforming to the angle between the two lower sides of said coil to be press formed when resting in said lower die, thrust means for adjusting said lower die transversely of the vertical plane bisecting said recess in said press head from side to side thereof, and holding and guiding means for maintaining said lower die in adjusted position against said thrust means, whereby when one side of a substantially rectangular coil to be press formed is placed in said lower die and said upper die is positioned thereon, the actuation of said press head presses said dies together a predetermined amount to press form the four sides of said side of said coil, irrespective of whether or not the lowermost and uppermost horizontal edges of said side of said coil are in a vertical plane.

6. In a machine assembly of at least two machines for shaping armature coils or the like, each said machine having a press head adapted to co-

operate with a manually positioned upper die, a lower die adapted to cooperate with said upper die, a lower die forming with said upper die the exact configuration in which one side of an armature coil is to be pressed therebetween, the improvement comprising, positioning at least two of the said machines side by side with the press heads, upper dies and lower dies in lengthwise registry, and interconnected means for energizing said press heads at the same time, whereby an armature coil having one side of greater length than can conveniently be handled by one machine can be press formed by at least two of said machines positioned side by side as aforesaid.
